UNITED STATES PATENT OFFICE

2,342,150

WETTING COMPOSITION

Werner E. Kleinicke, Coalwood, W. Va., assignor
to The Johnson-Marsh Corporation, New York,
N. Y., a corporation of Delaware

No Drawing. Application October 24, 1940,
Serial No. 362,622

4 Claims. (Cl. 252—354)

This invention relates to a new composition. While the composition according to this invention is adapted for various uses where a wetting agent is desired, it will be found to be of special advantage for the wetting of coal, coke, rock, iron, sulphur, lime, molybdenum sulphide, and the like, dust and dusts commonly carried in the air in industrial and mining operations.

The composition according to this invention finds special advantage for the rapid and effective wetting of, for example, coal dust in coal mines for the prevention of formation of explosive mixtures of coal dust and air and for the rapid and effective wetting of various rock dust for the prevention of negative physiological effects, as, for example, silicosis.

Heretofore it has been known that esters of sulfodcarboxylic acids have a superior wetting power adapting them for various use as wetting agents. However, such esters in many cases are usable only with great difficulty or are substantially useless as agents for facilitating wetting with water, since variously they are of low to substantially no solubility in cold water.

Now in accordance with this invention, it has been found that esters of sulfodcarboxylic acids which are of low to substantially no solubility in cold water may be rendered soluble, or more readily soluble, in cold water through the medium of their association with urea. Hence, this invention comprises a new composition comprising essentially an ester or mixed ester of a sulfodcarboxylic acid, and their basic salts, characterized by low solubility in water, and urea.

The composition according to this invention may also include an antifreeze, as a polyhydric alcohol, soluble in water.

For use as a wetting agent, the composition will be highly diluted with water and desirably, though not essentially, will initially include some water.

The esters comprising an essential ingredient of the composition according to this invention are fully described together with procedure for their preparation in U. S. Patent No. 2,028,091, January 14, 1936, to Jaeger.

The urea ingredient of the composition, as has been indicated, will perform the function of rendering the esters soluble or more readily soluble in water, while the antifreeze, which may, for example, be ethylene glycol, glycerine, or the like, will protect the composition, when water is included, from freezing under low temperature.

By way of example, the esters and basic salts thereof having low or no solubility in water con-

templated as components of compositions in accordance with this invention will comprise compounds, of the type indicated, each of the alkyl radicals of which is octyl or higher, such as, for example, the sodium salts of dioctyl, dilauryl, distearyl sulfosuccinate. Again, the composition will comprise other compounds of the type indicated, such, for example, as ethyl stearyl sulfosuccinate, dibutyl sodium sulfosuccinate, fenchyl sodium sulfosuccinate, glycol sulfosuccinate, calcium diamyl sulfosuccinate, calcium dihexyl sulfosuccinate, and the like esters, mixed esters, basic, as, for example, sodium, potassium, ammonium, calcium, and the like, salts thereof, and certain metal, as iron, salts thereof, characterized by low to substantially no solubility in water.

The essential components of the composition according to this invention, i. e., ester, mixed ester, basic, and certain metal salts thereof of low or no solubility in water, and urea, may be in widely varying proportions, though generally speaking they will desirably be present in the proportion on the basis of about 0.85 pound of ester, mixed ester, or salt thereof, to 1.5—3.0 pounds of urea.

Where an antifreeze, as ethylene glycol, glycerine, or the like, is included, it may be included in widely varying proportion, but desirably will be present in the proportion of from 1.0—3.0 pounds on the basis of 0.85 pound of ester to 1.5—3.0 pounds of urea.

Where, as is desirable, water is initially included in the composition, it may be included in widely varying amounts. Preferably, however, it will be included in amount sufficient to make a total of one gallon including the other ingredients on the basis of the proportions given above.

As illustrative of compositions according to this invention, for example, clear solutions which will be miscible with water in all proportions may be made up on the following formulae:

Formula A

	Pounds
Sodium dioctyl sulfosuccinate	0.85
Urea	3.0
Water sufficient to make a total of one gallon	

Formula B

	Pounds
Sodium dioctyl sulfosuccinate	0.85
Urea	2.0
Ethylene glycol	2.0
Water sufficient to make a total of one gallon	

Formula C

	Pounds
Sodium dioctyl sulfosuccinate	0.85
Urea	1.5
Ethylene glycol	3.0
Water sufficient to make a total of one gallon	

As illustrative of the preparation of compositions according to this invention where water may be included, 0.85 pound of, for example, sodium dioctyl sulfosuccinate may be first added to about 3.5 pounds of water. Desirably the water will be heated, say, for example, to about 180° Fahrenheit, in order to promote partial solution of the sodium dioctyl sulfosuccinate. To the milky and strongly foaming solution are added 3 pounds of urea without further application of heat, whereupon the partial solution will turn glass clear and become very limpid. Finally, the solution is diluted with enough water, about 20 2 pounds, to make one gallon of final composition. As an alternative, urea and sodium dioctyl sulfosuccinate may be heated together with the total of the required water to make one gallon of concentrate, or the non-aqueous ingredients may be blended without water, shipped in such condition and dissolved in water as needed for their use as required.

As illustrative of the preparation of compositions in accordance with this invention where an antifreeze is included, for the purpose of safe storage at extremely low winter temperatures, 0.85 pound of, for example, sodium dioctyl sulfosuccinate is added to 2 pounds of an antifreeze, for example, ethylene glycol, and 3.5 pounds of water, preferably with heat as above. Then 2 pounds of urea are added, and after this has gone into solution, the mixture is diluted with sufficient water, say about 1.25 pounds, to make one gallon of composition. Again, as an alternative, the non-aqueous constituents of the composition may be intimately blended first, shipped in this condition, and transformed into aqueous concentrates or dilute solution as need arises dissolving in water.

For use, the composition in accordance with this invention, for example, for the wetting of dust, will desirably be highly diluted with water. Thus, for example, the composition whether blended with water or without any consequential amount of water will, for use, be dissolved in water in the proportion, for example, on the basis of about 1 pound of its ester or salt component content to about 10,000 parts of water, by weight. Thus, for example, the composition on

Formula A, containing 0.85 pound of sodium dioctyl sulfosuccinate, when blended without water, would desirably be dissolved in about 8,350 pounds of water.

Again considering the compositions of Formulæ B and C, variously containing urea and water and urea, ethylene glycol and water, these compositions may, for use, desirably be diluted on the ratio of 1 part of the composition as a whole to about 1000 parts of water by weight, since they contain sodium dioctyl sulfosuccinate in amount of about 10%.

It will be understood that where in the claims appended hereto the term "ester" is used, it is intended that such term shall include mixed esters and basic and metal salts of esters and mixed esters as equivalents.

It will be understood that the compositions detailed above for illustrative purposes and the illustrative modes of preparation and use are not intended as limiting upon the scope of this invention.

What I claim and desire to protect by Letters Patent is:

1. A wetting composition comprising an alkali salt of an ester of sulfosuccinic acid from the group consisting of alkali salts of dihexyl and dioctyl sulfosuccinates, urea and a water-soluble polyhydric alcohol from the group consisting of glycerine and ethylene glycol in proportion on the basis of 0.85 part by weight of alkali salt, 1.5-3 parts by weight of urea and 3.0-1.0 parts by weight of polyhydric alcohol.

2. A wetting composition comprising an alkali salt of dioctyl sulfosuccinate, urea and a polyhydric alcohol from the group consisting of glycerine and ethylene glycol in proportion on the basis of 0.85 part by weight of alkali salt, 1.5-3.0 parts by weight of urea and 3.0-1.0 parts by weight of polyhydric alcohol.

3. A wetting composition comprising an alkali salt of dihexyl sulfosuccinate, urea and a polyhydric alcohol from the group consisting of glycerine and ethylene glycol in proportion on the basis of 0.85 part by weight of alkali salt, 1.5-3.0 parts by weight of urea and 3.0-1.0 parts by weight of polyhydric alcohol.

4. A wetting composition comprising sodium dioctyl sulfosuccinate, urea and ethylene glycol in proportion on the basis of 0.85 part by weight of sodium dioctyl sulfosuccinate, 2 parts by weight of urea and 2 parts by weight of ethylene glycol.

WERNER E. KLEINICKE.
